(57) **CLAIM**

The ornamental design for a figurine, as shown and described.

DESCRIPTION

FIG. 1 is a perspective view of a figurine showing my new design;

FIG. 2 is a front view of the figurine shown in FIG. 1;

FIG. 3 is a rear view of the figurine shown in FIG. 1;

FIG. 4 is a right side view of the figurine shown in FIG. 1;

FIG. 5 is a left side view of the figurine shown in FIG. 1;

FIG. 6 is a top view of the figurine shown in FIG. 1; and,

FIG. 7 is a bottom view of the figurine shown in FIG. 1.

It will be understood that the dashed lines presented in the drawings are for illustration only and do not form a part of the claimed design.
